COMBINATION DRAIN AND STRAINER

Joseph E. Frances, Oakland, Calif.

Application March 8, 1938, Serial No. 196,356

7 Claims. (Cl. 285—25)

The invention relates to a combination drain and strainer of the type commonly employed for sinks, basins and other types of containers and plumbing fixtures.

5 An object of the invention is to provide a drain and strainer of the character described which may be quickly and readily installed without necessarily requiring expensive and specialized labor with simple and ordinary tools, and at the 10 same time provide a fitting of the character described which will be absolutely sealed against leakage and one that will last substantially indefinitely.

Another object of the invention is to provide a 15 drain of the character above which may be readily removed and replaced without the use of putty or paint or other sealing compounds.

A further object of the invention is to provide a drain fitting of the character described in which 20 all torsional strain is eliminated in sealing the fitting in a sink or the like, thereby enabling the use of substantially lighter weight material which may be fashioned by stamping, spinning or drawing, and hence providing a fitting which is easier 25 and cheaper to manufacture than similar types fittings heretofore available.

The invention possesses other objects and features of advantage, some of which, with the foregoing, will be set forth in the following description 30 of the preferred form of the invention which is illustrated in the drawings accompanying and forming part of the specification. It is to be understood, however, that variations in the showing made by the said drawings and description may 35 be adopted within the scope of the invention as set forth in the claims.

Referring to said drawings:

Figure 1 is a vertical cross sectional view of a 40 combination drain and strainer constructed in accordance with the present invention.

Figure 2 is a fragmentary front elevation of a part of the refuse basket support.

Figure 3 is a cross sectional view of the assembly 45 taken substantially on the plane of line 3—3 of Figure 1.

Figure 4 is a plan view of one of the locking rings used in the assembly.

Figure 5 is a side elevation of a part of the 50 locking ring illustrated in Figure 4.

Figure 6 is a partial vertical sectional view of a modified form of support for the drain.

Figure 7 is a view similar to Figure 6 but showing the parts in position prior to final assembly.

55 Figure 8 is a perspective view of one of the

members used in the modified form of construction.

Figure 9 is a partial vertical sectional view of a further modified form of support for the drain.

Figure 10 is a plan view of one of the parts used 5 in the form of construction illustrated in Figure 9.

The combination drain and strainer of the present invention and as illustrated in the accompanying drawings, comprises a tubular member 10 15 11 which is adapted for mounting through an opening 12 in a wall 13 of a container or the like, the wall 13 being here arranged as in typical sink construction with an enlarged annular embossment 14 surrounding the opening 12 and a beveled 15 surface 16 on the inner side 17 of the wall providing a shallow socket surrounding the opening. The upper end of the tubular member is provided with a transversely extending flange 18 which is adapted to seat against the beveled surface 16 of 20 the wall in said socket so as to dispose the outer peripheral edge 19 of the flange substantially flush with the inner side 17 of the wall.

In accordance with the present invention, 25 means is provided for sealing the tubular member in the opening 8 without the use of putty or paint or other sealing materials and to seal the member in the opening in such a manner that the member may be readily removed and replaced if desired.

This means consists briefly in the use of a 30 non-torsional, longitudinally expandible device mounted on the member below the wall 12 which functions together with an appropriate gasket for clamping the wall between the flange 18 and the gasket compressed at the under side of the 35 wall.

In the present construction, a gasket 22 of annular form and compressible material, such as rubber or the like, is mounted around the member 11 at the under side of the embossment 14 and is provided with a tapered top portion 23 40

adapted to enter the opening 12 between the member 11 and the embossment to seal the tubular member in the opening. The longitudinal 45

expandible means mounted on the member for compressing the gasket in the opening 12 and 45 against the under side of the embossment as

35 aforementioned, consists of a backing ring 24 surrounding the member 11 and movable longitudinally thereon against the under side of the gasket and which is pressed upwardly against the 50

gasket in the present form of the invention, by means of a plurality of screws 26 carried by a 55 fixed annular ring member 27 mounted on the tubular member in longitudinally spaced relation to the backing ring 24. The ring 27 may be fixed

on the tubular member in any suitable manner as by sweating or clamping the ring in place or by use of offsets or abutments on the member. Preferably the side wall of the tubular member is itself provided with a transverse offset in one form or another for supporting the ring, such as here shown by the provision of an annular recess 28 in the side wall of the member in which the ring is mounted. To secure the ring in such recess, the ring is preferably formed of a plurality of sections 29 and 31 so that the same may be assembled around and clamped in the recess 28. Preferably, the opposite ends 32 and 33, and 34 and 36 of the sections are provided with longitudinal shoulders which may be clamped together by screws 37 passed therethrough. In view of simplicity and cheapness, both of the ring members 24 and 28 are preferably formed of flat annular stock and are reinforced by the provision of inner and outer circumferential flanges 38 and 39, and 41 and 42, the former seating directly in the recess and the latter extending around the base of the gasket 22 to hold the same in place. The screws 26 may be threaded through the body 25 of the ring 27 or if desired in view of the relative thinness of the ring, the screws may be carried in threaded inserts in the body of the ring or threaded through nuts supported by the ring. It will now be clear that the installation of the fitting is extremely simple and requires merely the placing of the member 11 through the opening 12 to seat the flange 18 on the beveled surface 16 of the container wall, fastening the sectional ring 27 in place in the recess 28 of the member and then extending the screws 26 against the under side of the backing ring 24 so as to compress the gasket 22 into the opening and clamp the container wall between the flange 18 and the gasket. Removal of the fixture from the container wall is readily effected by a reversal of the aforesaid operations, including a release of the screws 26 and a removal of the clamping ring 27 to enable withdrawal of the member 11 from the opening. The ease and facility of installing and removing the fitting is of substantial importance, due to the fact that such fittings are frequently damaged either at the time of installation or subsequently, and with the present construction the fitting may be removed and replaced by one not having special knowledge and experience in plumbing devices and accomplished by the use of simple and ordinary tools without putty or paint or other sealing compounds.

55 The member 11 in addition to providing a drain for a container with which it is attached, is preferably formed with a top refuse receptacle for receipt of a combination refuse basket and plug. As here shown the member is provided with an enlarged upper portion 43, substantially of the size of the opening 12, and providing such a refuse receptacle in the drain and which connects with a reduced cylindrical portion 44 normally designated the "tail piece" of a drain fitting. Between the portions 43 and 44 the member 11 is formed with a longitudinally inclined or tapered wall portion 46 which is adapted to support a refuse basket 47 mounted in the enlarged portion 43. The basket 47 is provided with a bottom wall 48 and a perforate annular side wall 49 and is preferably slightly smaller in diameter than the enlarged portion 43 of the member, so as to seat the lower bottom edge 51 of the basket medially on the inclined wall 46. The upper 75 end 52 of the side wall 49 of the basket is pref-

erably flared outwardly to snugly engage the inner side wall of the enlarged portion 43.

Means is preferably provided for opening and closing the drain by either raising the basket from wall portion 43 or drawing the same there-to. As here shown, there is mounted across the tubular member in the refuse portion 44 thereof adjacent the base of the inclined wall 46, a bar strainer 53 which is preferably fixedly secured in the tubular member, such as here shown by rolling an inwardly extending bead 54 in the wall portion of the tubular member into an annular recess 56 provided around the periphery of the bar strainer 53. In the present construction the means for raising and lowering the basket consists of a stem 57 which is secured to the bottom wall 48 of the basket and which extends longitudinally through a central opening 58 in the bar strainer, the upper end of the stem being extended through an opening 59 in the bottom wall 48 of the basket and threaded into the base of a knob 61 in the basket so as to clamp the bottom wall 47 therebetween. Secured to the stem adjacent the strainer 53 are a plurality of wing-like projections or lugs 62 which may be passed through enlarged side portions 63 of the opening 58 when the basket is in seated position, and which are adapted to engage with thread portions 64 in the opening upon rotation of the stem, so as to draw the basket down tightly against the inclined wall portion 46. In elevating the basket the same is rotated and lifted by means of the knob 61 to position the lugs 62 on the top surface of the strainer where the same may be supported intermediate the side opening 63 to support the basket in elevated position over the inclined wall portion 46.

A modified form of longitudinal expansible joint is illustrated in Figures 6 to 8 of the drawings, wherein the tubular drain member 11' is drawn tightly against the upper surface of a container wall 13' about a drain opening by means secured against longitudinal displacement on the member at the under side of the wall and operating to wedge a gasket 23' longitudinally against the under side of the wall 13' and into the drain opening of the wall, so as to seal the fitting in the container wall opening. A form of securing means here illustrated provides a straight longitudinal force against the backing ring 24', as in the first embodiment, so that the tubular member is not subjected to any torsional stress and may, therefore, be constructed of light weight material. The means for forcing the backing ring 24' longitudinally towards the under side of the container wall here consists of a plurality of cylindrical sections 66 which are adapted to fit around the tubular member 11' and are provided with an outwardly and upwardly sloping top flange 67 which is adapted to engage a complementary sloped under side 68 on the backing member 24'. The sections 66 are held against longitudinal displacement by means of a lug 69 carried by each of the sections and engageable in the circumferential recess 28' provided in the front member. Surrounding the sections 66 is a sleeve 71 which is driven longitudinally over the sections so as to cause them to snugly embrace the drain member 11' and press upwardly against the backing ring 24'. The assembling of the several parts is illustrated in Figure 7. The gasket and backing ring are first positioned on the tubular drain member adjacent the under side of the wall 13' and the sections 66 are next assembled with the lugs 69 seated in the recess 28' and

the inner lower edge of the flange 67 engaged with the under side of the backing ring. In this initial position the sections 66 incline outwardly from the side of the drain member, as shown in 5 Figure 7. The sleeve 71 is then slid longitudinally over the drain member so as to engage the upper end 72 of the sleeve around the base of the sections 66. The sleeve is then driven longitudinally so as to cause the sections 66 to fulcrum 10 inwardly about the lugs 69 and to thereby wedge the backing ring 24' and the gasket longitudinally against the under side of the container wall.

A further modified form of the support for the drain member 11" is illustrated in Figure 9, 15 wherein the relatively fixed supporting ring 27" is held against longitudinal movement on the member by means of a split ring 76 carried in the annular recess 28". The split ring 76 is preferably of circular cross section and the ring 20 27" is preferably provided with a collar portion 77 which jointly engages the side of the member 11" and the outer side of the ring 76, so as to confine the ring in the recess and to hold the member 27" against longitudinal displacement. 25 The ring as illustrated in Figure 9 is preferably of a size causing the ring to protrude laterally from the recess and from the side wall of the member 11". A plurality of screws 26" are carried by the ring member 27" as in the first embodiment, and as here shown the screws are 30 threaded through nuts 78 which are supported on the upper surface of the ring member. As a further feature of distinction over the first embodiment, the upper ends 79 of the screws are 35 mounted in an annular recess 81 in the backing ring 24" so as to hold the screws against radial displacement on the backing ring. The recess 81 is preferably formed in the backing ring so as to provide a protuberance on the top surface 40 of the backing ring which tends to crowd the gasket 23" towards the wall of the member 11" and towards the container wall 13". Also, the gasket 23" is preferably widened at the inner edge thereof surrounding the member 11" 45 and is arranged with both of its top and bottom surfaces 82 flared or inclined divergently towards the inner edge of the gasket. The upper surface of the backing ring 24" is preferably beveled to conform to the flared or inclined abut- 50 ting surface of the gasket. Preferably, the gasket and rings and screws, etc., are completely enclosed within a casing 83 which is provided in the present embodiment with a cylindrical side wall 84 which is adapted to slide over the rings 55 24" and 27" and to extend from the under side of the wall 13" to below the heads of the screws 26". The lower end wall 86 is provided with a central opening for engaging over the member 11". By the use of the member 83 the 60 several parts of the fitting are shielded from view and may be left in unfinished metal without detracting from the appearance of the fitting.

I claim:

1. A drain for a container having an opening in a wall thereof, a tubular member adapted for mounting through said opening and having a flange at an end for engaging one side of said wall surrounding said opening, an annular compressible gasket surrounding said member and adapted to engage the opposite side of said wall at said opening, an annular backing ring surrounding said member and movable longitudinally thereon against said gasket, a plurality of sections arranged around said member and fulcrummed on said member for movement from an

outwardly inclined position thereon to a substantially parallel position relative to said member and having a length and longitudinal position on said member to engage said backing ring adjacent said parallel position to cause upon movement of said sections to said parallel position a longitudinal movement of said backing ring and gasket against said wall, and means for fulcruming said sections from said inclined position to said parallel position. 10

2. A drain for a container having an opening in a wall thereof, a tubular member adapted for mounting through said opening and having a flange at an end for engaging one side of said wall surrounding said opening, an annular compressible gasket surrounding said member and adapted to engage the opposite side of said wall at said opening, an annular backing ring surrounding said member and movable longitudinally thereon against said gasket and being provided with a longitudinally inclined surface, said member being provided with an annular recess, a plurality of sections surrounding said member and each having a lug engageable in said recess to fulcrum said sections for movement from an 25 outwardly inclined position on said member to a substantially parallel position relative to said member, each of said sections having an outwardly and longitudinally extending flange engageable with said inclined surface on said ring upon 30 fulcruming of said sections from said second to first position, and a sleeve adapted for mounting over said sections for causing a displacement thereof to said parallel position and a longitudinal displacement of said backing ring. 35

3. A drain for a container having an opening in a wall thereof, a tubular member adapted for mounting through said opening and having a flange on an end for engaging one side of said wall surrounding said opening, an annular compressible gasket surrounding said member and adapted to engage the opposite side of said wall at said opening, an annular backing ring surrounding said member and movable longitudinally thereon for positioning of one side thereof 40 against said gasket, the opposite side of said ring being provided with an annular recess, means fixedly supported on said member in longitudinally spaced relation to said backing ring, and a plurality of screws carried by said means 45 and extendible longitudinally thereof into engagement with said backing ring in said recess. 50

4. A drain for a container having a circular opening in a wall thereof comprising, a cylindrical member of sheet metal or the like having a 55 flange at one end thereof and adapted for extension through said opening, a rolled annular depression in said tubular member and spaced from said flange, a compressible gasket surrounding said member and engageable with the wall of said container, an annular backing ring confining and supporting said gasket and slideable on said tubular member, a clamping ring adapted to be tightened around said tubular member in said annular depression, and threaded means 60 held by said clamping ring to force said gasket and annular flange against opposite sides of the container wall adjacent said opening. 65

5. In combination with a sink having a discharge opening through a bottom wall thereof 70 and formed with a beveled edge portion surrounding said opening at the inner side of said sink wall, a drain fitting comprising a sheet metal tube adapted for insertion through said opening and having a circumscribing flange at one end 75

thereof beveled to fit against said edge portion with said tube extending through said opening to the side of said wall, an annular compressible gasket surrounding said tube and adapted to engage said sink wall at the outer side thereof surrounding said opening and formed with a beveled surface adapted to fit into said opening and fit directly against the peripheral edge of said opening, an annular backing ring for said gasket surrounding said tube and slidably engaged over said tube, said tube being formed with an annular indentation spaced from said flange and of circular form in longitudinal cross-section, means extending around said tube and having a curved part fitting into said indentation to hold said means against longitudinal movement away from said flange and having a compression member engaging said backing ring for clamping said sink wall between said flange and said gasket.

6. A drain fitting for a sink having a discharge opening through a bottom wall thereof comprising, a sheet metal tube adapted for insertion through said opening and having a circumscribing flange at one end thereof adapted to fit against said wall at the inner side of said sink with said tube extending through said opening to the outer side of said wall, an annular compressible gasket surrounding said tube and adapted to engage said outer sink wall around said opening, an annular backing ring for said gasket surrounding said tube and slidably engaged over said tube, said tube having an annular seat formed therein in longitudinally spaced relation from said flange, a split ring mounted in said seat and held therein against a longitudinal displacement away from said flange and projecting

from the side of said tube member, an annular member mounted around said tube and formed with an annular seat at the inner peripheral edge thereof adapted to embrace said split ring to thereby interlock said tube seat and ring and member seat against longitudinal displacement away from said flange, and screws carried by said annular member and extending longitudinally to engage said backing ring for clamping said sink wall between said flange and gasket. 10

7. A drain fitting for a sink having a discharge opening through a bottom wall thereof comprising, a sheet metal tube adapted for insertion through said opening and having a circumscribing flange at one end thereof adapted to fit 15 against said wall at the inner side of said sink with said tube extending through said opening to the outer side of said wall, an annular compressible gasket surrounding said tube and adapted to engage said outer sink wall around said opening, an annular backing ring for said gasket surrounding said tube and slidably engaged over said tube, said tube having an annular indentation of arcuate form in longitudinal cross-section spaced longitudinally from said flange, 25 a split wire ring of round cross-section adapted to be sprung into said indentation, an annular member surrounding said tube member and formed with a seat at the internal periphery thereof adapted to fit over and embrace said wire ring, and screws carried by and extending longitudinally from said ring member to engage said backing ring for clamping said sink wall between said flange and gasket.

JOSEPH E. FRANCES.
